UNITED STATES PATENT OFFICE.

HERMAN H. UCKOTTER, OF CINCINNATI, OHIO, ASSIGNOR TO THE ANCHOR BUGGY COMPANY, OF SAME PLACE.

FIFTH-WHEEL FOR VEHICLES.

SPECIFICATION forming part of Letters Patent No. 435,988, dated September 9, 1890.

Application filed April 27, 1889. Serial No. 308,864. (No model.)

To all whom it may concern:

Be it known that I, HERMAN H. UCKOTTER, a citizen of the United States of America, and a resident of the city of Cincinnati, in the 5 county of Hamilton and State of Ohio, have invented certain new and useful Improvements in Fifth-Wheels and King-Bolt Couplings, of which the following is a specification.

The several features of my invention and 10 the various advantages arising from their use, conjointly or otherwise, will be apparent from the following description and claims.

In the accompanying drawings, forming 15 part of this specification, Figure 1 is a view, in perspective, of a fifth-wheel, head-block, part of the spring, part of the front axle, part of the double perch, king-bolt, and connections, illustrating my invention, the view being taken at a point to one side and somewhat 20 in the rear of said device. Fig. 2 is a front elevation of the combined device shown in Fig. 1. Fig. 3 is a vertical central section of the same, taken at right angles to the head-block and axle. Fig. 4 is a view, in perspective, of the parts shown in Fig. 1, with the 25 exception that a single perch is substituted for the double one, and certain modifications are present, the better to adapt my invention to said single perch, as will be hereinafter 30 more fully explained. Fig. 5 is a vertical central section of the combination of devices shown in Fig. 4, the section being taken through the center of the perch at right angles to the axle and head-block.

35 In the drawings only so much of the perch, front axle, and front spring are shown as are necessary in the illustration of my invention.

H represents the head-block.

I I' is the axle.

40 Both the head-block and axle may be of the ordinary form.

J represents the semi-elliptic spring secured to the top or upper portion of the head-block by the usual clips J² J², these clips being secured at the bottom of the head-block by means of the usual bars J' and nuts J³. Further description of the same is unnecessary in this connection.

45 a represents the upper half or circle of the fifth-wheel. This fifth-wheel consists, as or-

dinarily, of the full half-circle located at the rear of the head-block, and is continued forward under the head-block on each end thereof. The forward ends of this circle are connected by a scroll a⁷, and the head-block is 55 connected to and held in place by the fifth-wheel through the agency of the vertical bolts a⁸ a⁸, one of which is connected to the upper circle a on the one side, and the other bolt a⁸ is secured to the portion of the upper circle 60 on the other side of the fifth-wheel, the usual studs a⁶, attached to the upper circle a, being present. Two of these studs a⁶ form a recess at one side of the circle, the head-block fitting between the two and resting upon the 65 circle, and a similar pair of studs a⁶ a⁶ being present at the other side of the fifth-wheel, the head-block resting between this last-named pair. The lower half or circle of the fifth-wheel C³ lies, as usual, directly beneath 70 the upper circle a, and rests upon and is connected to and held in place by the axle l.

75 Into the recesses C⁵ on the lower surface of the portion C⁴, on one side of the lower half of the fifth-wheel, one end of the axle-bed is received, and the other end portion of the axle-bed is received into a similar recess C⁵ in the portion C⁴ in the other side or limb of the lower circle C³ of the fifth-wheel.

Rigidly connected to the lower fifth-wheel 80 at the parts C⁴, and preferably integral therewith, is a cross strap or plate C², which rests upon the upper surface of the axle between the two portions or arms of the lower circle of the fifth-wheel. This plate C² is preferably 85 secured to the axle, preferably as shown by the embracing-clips G G', bolts G², one of which clips embraces the plate and axle near one end of the said plate, and the other embraces the said plate and axle near the other 90 end of said plate. Screws C⁶ are also preferably employed to secure the plate to the axle and prevent it from buckling up and away from the axle in the neighborhood of the king-bolt, one of said screws being a little to the 95 right of an imaginary vertical plane passing through the king-bolt and the longitudinal center of the vehicle, and the other screw being located a little to the left of said vertical plane.

The recesses C^5 C^6 , heretofore referred to, in connection with the said plate C^2 , clips, and screws, bind the axle-plate C^2 and the lower circle of the fifth-wheel firmly and rigidly together.

On the under side of the head-block lies a strap or plate a^2 , rigidly secured to and integral with the upper half or circle of the fifth-wheel, one end of the strap being joined to the fifth-wheel in the neighborhood of the recess formed by the studs a^6 at one side of the upper circle, and the other end of the strap attached to the other side of the fifth-wheel in the neighborhood of the recess formed by the studs a^6 at the other side of said upper circle or half of said fifth-wheel. The cross-plates J^3 J^8 of the clips J^2 are rigidly fastened to and are preferably integral with the plate a^2 , and in this way the plate a^2 is rigidly held to the bottom of the head-block by the same clips whereby the spring J is held to the top of the head-block.

Screws similar to C^6 C^6 , heretofore described, are preferably employed to prevent the plate a^2 from buckling away from the bottom of the head-block. One of the said screws being placed midway between the plate J^3 and its adjacent portion of the upper fifth-wheel and the other of said screws being placed between the plate J^4 and its adjacent portion of the fifth-wheel, in front of this plate a^2 , extending forward, as shown, and to which is secured the front brace e , the preferred mode of connection is as follows: The brace e is provided with the long eye e' , the bolt a^3 passing through the plate a^2 and the long vertical eye e' , and is secured in position by the nut a^4 , and the lower end of the brace e is continued downward and under the axle, terminating at the rear of the axle in the king-bolt sleeve E , for the reception of the lower end of the king-bolt.

Returning to the description of a^2 , this plate at its inner side is provided with the vertical face or flange a^9 , which lies against the inner or rear vertical face of the head-block. This flange a^9 is suitably secured to the head-block by means of horizontal bolts or screws a' passing into and preferably through the said head-block. This flange or plate carries the vertical king-bolt sleeve A for the reception of the upper end of the king-bolt. The strap or plate C^2 , heretofore described, connected with the lower fifth-wheel is likewise provided with the vertical plate or flange C' , lying at and against the rear vertical face of the axle-bed, and is secured to the axle-bed by bolts or screws C^7 in a similar manner to that in which the plate a , heretofore mentioned, is preferably secured to the head-block. This flange C' carries the rearwardly-projecting king-bolt sleeve C for the reception of the central portion of the king-bolt.

65 P P represent the two limbs or arms of the double perch.

B is a vertical king-bolt sleeve embracing

the king-bolt between the head-block king-bolt sleeve A and axle king-bolt sleeve C .

D is a vertical king-bolt sleeve, which lies between the head-block sleeve C and the bottom king-bolt sleeve E , and receives its portion of the king-bolt. From the king-bolt sleeve B extends rearwardly the strong arm b , rigidly united to the king-bolt sleeve B , and from the king-bolt sleeve D rearwardly extends the strong arm d , rigidly united to the king-bolt sleeve D . The arm b is rigidly united to the portion b' of the perches and is preferably integral therewith. The other arm d is rigidly united to the lower portion or plate d' of the perches. The portions b' and d' are formed of metal and provided with end wall or abutment, against which the perch or perches abut.

For the better securing the perches in connection with the fifth-wheel and to hold them more rigidly in place, the portion b' is combined with the upper perch-box b^3 b^2 , the part b^3 being the outer vertical wall of the box, and the part b^2 being the upper or top of the box.

The lower or supporting plate d' may, when desired, be provided with flanges similar to flanges b^3 , in such event contributing to form a lower perch-box. Each of the perches P is respectively inserted between its upper adjacent plate b^2 and lower plate b' , and its forward outer end resting against its adjacent exterior wall b^3 of the perch-box. The upper fifth-wheel is provided with an extension a^5 running rearwardly from its adjacent perch-plate b^2 and resting therein, and the adjacent upper perch-plate b^2 , also perch-plate b' , and said arm or brace a^5 are all secured compactly together by means of the bolt, as a^6 .

A similar arm or brace a^5 extends from the upper fifth-wheel rearwardly from the other perch P and rests upon the upper plate b^2 adjacent thereto, and this perch and its adjacent upper plate b^2 , also the plate b' and brace a^5 , are rigidly secured together by means of the similar bolts a^6 a^7 . Where bolts are used instead of screws, of course nuts, as a^7 , will be employed to secure them in place. Near the forward end of each perch is a bolt b^4 . One of these bolts b^4 secures together one of these perches and its adjacent upper and lower plates, while the other of the bolts b^4 secures rigidly together the other perch to the adjacent upper and lower plate. In this way and by these means the perches of the upper fifth-wheel are rigidly secured together in one firm and compact unyielding structure provided at forward end with rigid king-bolt sleeves B and D . The lower portion of the king-bolt sleeve A is provided with a socket 1. The upper end 3 of the king-bolt sleeve is diminished in size and fits closely within the socket 1 of sleeve A , the edge of the ring 2 of sleeve A resting on the shouldered portion 4 of sleeve B . The lower end 5 of sleeve B is diminished and fits closely within a socket 7 in the upper part of the sleeve C , the edge of ring 2 of sleeve C resting against the shoulder

110

115

120

125

130

6 of sleeve B. The upper end 11 of sleeve D is diminished in diameter and fits closely within the socket 9 in the lower end of sleeve C, the edge of ring 10 of sleeve C resting 5 against the shoulder 12 of sleeve D. The upper end 15 of sleeve E is diminished in size and fits closely within the socket 13 in the lower end of sleeve D, the ring 14 of sleeve D resting on the shoulder 16 of sleeve E. 10 While all the sleeves thus interfit closely they do not fit one another so tightly as to prevent their turning easily upon one another.

The object of the diminished ends of the sleeves and of the sockets receiving these diminished ends is to prevent the sleeves from slipping by one another, as hereinafter more particularly set forth. Hence the position of the diminished parts and sockets may be reversed or interchanged in relation to the 15 sleeves. Thus, for instance, the sleeve A might carry diminished part 3, and sleeve B carry socket 1, and so on. It is not material which sleeve carries the socket and which sleeve carries the part entering said socket, 20 the main feature of this construction being the interlocking of the sleeves to prevent their slipping by one another in case the king-bolt breaks.

All of the king-bolt sockets or sleeves A B 30 C D E being placed vertically, as shown, the king-bolt F is inserted in place and suitably secured therein, preferably as follows: its upper end of head F resting on king-bolt sleeve A, while its lower end projects below the 35 brace E, and provided with screw-thread, as indicated by the nut f', which, upon being tightened, holds the perches, fifth-wheel, axle, and head-block firmly together. At the same time, the axle and lower fifth-wheel are free 40 to turn in the usual manner upon the upper fifth-wheel.

Some of the advantages resulting from my invention are as follows:

All of the parts are combined with one bolt. 45 All the sockets take up the wear and prevent rattle of the parts, and a more secure coupling is also obtained.

The present location of the fifth-wheel at the rear of the head-block and axle, and the location 50 of the king-bolt and its embracing sleeves at the rear of the axle and head-block, make a very central and strong attachment.

The brace or braces, rigidly united to the upper half of the fifth-wheel as well as to 55 guard e, prevent the sleeves from leaving one another; hence when the king-bolt is broken or lost out, the sleeves of the sockets are prevented from leaving one another, and their interlocking portions will keep the head-block, 60 axle, and fifth-wheel in their normal position and prevent accident. Should any accident occur, all parts must break, making five chances of safety in the present device over the ordinary fifth-wheel and king-bolt connections now in use.

When it is desired to combine my fifth-wheel and king-bolt coupling with a vehicle

in which a single perch is employed, the preferred mode of combining the same is shown in Figs. 4 and 5. The portions—namely, the 70 sleeves B D, arms b d, and end b'—are made as heretofore, and in place of the two plates b² b² and the two plates d² d², one upper and one lower are required to be used, each of these plates being preferably provided 75 with the usual side flanges or walls b³ b³, converting the plates b² and d², respectively, into recessed structures or boxes for the reception of the perch P. One of the braces a⁵ will be omitted, and such a brace, starting 80 from the center of the rear portion of the fifth-wheel, will be at the rear suitably secured to the perch P, and the bolt a⁶ will bind rigidly together the plates b² d² and perch P and braces a⁵. In the event of using a single perch, it is desirable to provide a brace a⁸, extending forward from the center of the rear part of the upper fifth-wheel, and this brace will be rigidly secured to the perch by the bolt b⁴, which latter will bind rigidly 85 together the perch-plates b² d² and the arm a³. For the further bracing of the single perch, I prefer to also add the lower brace e³, rigidly united to the lower sleeve E, and extending rearwardly from said sleeve to the underside 90 of the perch-plate b'. A convenient mode of attachment of said perch is by the same perch a⁶, whereby the upper fifth-wheel brace a⁵ is connected to said perch. A desirable support for the lower half of the fifth-wheel is 95 furnished in the pillow b⁶, which is rigidly fastened to or formed with the plate b². The top of this pillow is recessed, substantially as shown, and in this recess the under portion of the lower half C³ of the fifth-wheel 100 rests and moves. In other respects the construction of the device, as shown in Figs. 4 and 5, is precisely like those shown in Figs. 1, 2, and 3.

While the various features of my invention are preferably employed together, one or more of said features may be used without the remainder, and, in so far as applicable, one or more of said features may be used in connection with fifth-wheels other than the 110 one herein specifically specified.

What I claim as new, and desire to secure by Letters Patent, is—

1. The combination of the head-block carrying the rearwardly-projecting sleeve A, and the axle carrying the rearwardly-projecting sleeve C, and the perch carrying the forwardly-extending sleeves B and D, and the fifth-wheel having its rear half-circle extending rearwardly of the head-block and axle, 120 the lower half of the fifth-wheel being connected to the head-block and at rear connected to the perch by a brace or braces a⁵, substantially as and for the purposes specified.

2. The combination of the head-block, the 130 upper fifth-wheel circle having its rear portion extending back of the head-block and connected thereto, plate a², connected to the head-block and carrying king-bolt sleeve A,

- located at the rear of the said head-block and axle, and the lower half of the fifth-wheel connected thereto, and plate C², connected to the axle and provided with king-bolt sleeve C, 5 located at rear of said axle, and guard e, located in front of and underneath said axle and provided with king-bolt sleeve B, interposed between sleeves A and C, and also with sleeve D, interposed between sleeves C and E, substantially as and for the purposes specified.
3. The combination of the head-block, upper fifth-wheel circle, plate a², carrying king-bolt sleeve A, located at the rear of the axle, 10 axle and lower half of the fifth-wheel connected thereto, plate C², located upon the axle and connected thereto, and provided with king-bolt sleeve C, located at rear of axle, and the guard e, provided with king-bolt sleeve E, also located at rear of axle, and the perch 15 provided with sleeve B, located between sleeves A and C aforementioned, the perch being likewise provided with sleeve D, located between said sleeves E and C, the rear portion of the fifth-wheel being located in 20 rear of the axle and head-block and in proximity to the perch, the upper half of the fifth-wheel being provided with a brace or braces a⁵, connecting the fifth-wheel to the perch, substantially as and for the purposes specified.
4. The combination of the head-block carrying the upper fifth-wheel, the upper fifth-wheel having plate a² rigidly united thereto and provided with king-bolt sleeve A, located 25 at rear of the head-block, and the axle carrying lower fifth-wheel provided with plate C² rigidly united thereto, said plate C² carrying king-bolt sleeve C, located at rear of the axle, and the perch having king-boltsleeves B and 30 D united to the casting of the perch, sleeve B being located between the sleeves A and C, and sleeve D between the sleeves B and E, and king-bolt passing through said sleeves A, B, C, and D, and being independent of 35 and separate from the head-block and axle.
5. In combination, the head-block carrying the king-bolt sleeve C, and the perch carrying sleeves B and D, all of said sleeves being located at the rear of the axle, and the several sleeves interlocking one another by means 40 of diminished end portions, and sockets for the diminished end portions, substantially as and for the purposes specified.
6. The combination of the head-block carrying the upper fifth-wheel, the upper fifth-wheel having plate a² rigidly united thereto and provided with king-bolt sleeve A, located 45 at rear of the head-block, and the axle carrying lower fifth-wheel provided with plate C², rigidly united thereto, said plate C² carrying king-bolt sleeve C, located at rear of axle, and the perch having king-bolt sleeves B and D united to the casing of the perch, sleeve B being located between the sleeves A and C, 50 and sleeve D between the sleeves B and E, the rear portion of the fifth-wheel being located at the rear of axle and head-block and

provided with brace or braces a⁵, extending from the fifth-wheel to the perch and secured thereto, substantially as and for the purposes 70 specified.

7. In combination, the head-block carrying the upper king-bolt sleeve A, the axle carrying the king-bolt sleeve C, and the perch carrying the king-bolt sleeves B and D, the several sleeves interlocking with one another by means of diminished end portions and sockets for the reception of said diminished end portions, substantially as described, and the upper fifth-wheel rigidly united to the perch, 75 substantially as and for the purposes specified.

8. In combination, the head-block carrying the upper king-bolt sleeve A, the axle carrying the king-bolt sleeve C, and the perch carrying the king-bolt sleeves B and D, guard e, provided with king-bolt sleeve E, the several sleeves interlocking with one another by means of diminished end portions, substantially as described, and the upper fifth-wheel 80 rigidly connected to the perch, substantially as and for the purposes specified.

9. The combination of the head-block and axle, sleeves A, B, C, D, and E, located at rear of the axle, the sleeve A, connected to the head-block and capped over the sleeve B, sleeve B, connected to the perch and socketed in sleeve C, sleeve C, connected to the head-block and capped over sleeve L, which latter sleeve is connected to the perch, and sleeve 95 E, socketed within the sleeve D and rigidly connected to guard e, extending forward and at its upper end connected to plate a², attached to the lower side of the head-block and rigidly connected to sleeve A, and king-bolt, substantially as and for the purposes specified.

10. The combination of the head-block and axle, the sleeves A, B, C, D, and E, located at rear of the axle, the sleeve A, connected to the head-block and capped over the sleeve B, sleeve B, connected to the perch and socketed in sleeve C, sleeve C, connected to the head-block and capped over sleeve D, which latter sleeve is connected to the perch, and sleeve 100 E, socketed within sleeve D and rigidly connected to guard e, extending forward and at its upper end connected to plate a², attached to the lower side of the head-block and rigidly connected to sleeve A and king-bolt, and the guard e³, connected to the sleeve E and to the perch, substantially as and for the purposes specified.

11. In a fifth-wheel and king-bolt device, the sleeve A of the head-block, and sleeve C 110 of the axle and fifth-wheel, the latter and said sleeves A and C being at rear of head-block, and perch connected to upper portion of fifth-wheel and having sleeve B conjunctively interposed between sleeves A and C, and sleeve 115 D, connected to perch, and the king-bolt passing through said sleeves, substantially as and for the purposes specified.

12. In a fifth-wheel and king-bolt device,

the head-block carrying sleeve A, and the axle carrying sleeves C and E, all of said sleeves being located at the rear of said head-block and axle, and fifth-wheel located at the rear 5 of said head-block and braced to said perch, and the perch-connections B D, with the king-bolt sleeve B interlocking between sleeves A and C and sleeve D between sleeves C and E, substantially as and for the purposes specified.

13. In a combined king-bolt and fifth-wheel interlocking device, the combination of the upper fifth-wheel provided with plate a^2 , rigidly attached thereto, and having flange a , 15 provided with king-bolt sleeve a^2 , being rigidly united to plates or bars J^3 , of the clips J^2 for holding the spring to the head-block, the upper fifth-wheel being provided with the braces a^5 , rigidly connected to the perch, the 20 upper perch-plate carrying arm b , terminating in sleeve B , and lower perch-plate carrying arm d , terminating in king-bolt sleeve D , and the axle carrying the lower fifth-wheel, having rigidly attached thereto or integral there- 25 with the plate C^2 , and the flange C' , carrying the king-bolt and sleeve C, and the guard-iron e , carrying the king-bolt sleeve E, and at its upper end rigidly united to the forward extension of the plate a^2 , the respective 30 sleeves of the king-bolt interlocking with their adjacent sleeves, substantially as and for the purposes specified.

14. In a fifth-wheel and king-bolt device, the location of the king-bolt and its sleeves 35 at the rear of the head-block and axle and the location of the fifth-wheel at the rear of said axle, the upper half of the fifth-wheel being braced to the perch and the perch-connection with the king-bolt being made to in- 40 terlock with the adjacent sleeves of the head-block and axle, the perch-connection B being interposed between the sleeve of the head-block and the sleeve of the axle, the upper fifth-wheel circle being extended forward in 45 front of the axle and head-block, substantially as and for the purposes specified.

15. In a fifth-wheel and king-bolt device, the location of the king-bolt and its sleeves at the rear of the head-block and axle and 50 the location of the fifth-wheel at the rear of said axle, the upper half of the fifth-wheel being braced to the perch and the perch-connection with the king-bolt made to interlock with the adjacent sleeves of the head-block 55 and axle, the upper fifth-wheel being provided with the forward brace a^8 and the lower sleeve E being provided with the brace e^3 , substantially as and for the purposes specified.

60 16. In a fifth-wheel and king-bolt device, the location of the king-bolt and its sleeves at the rear of the head-block and axle and the location of the fifth-wheel at the rear of said axle, the upper half of the fifth-wheel 65 being braced to the perch and the perch-connection with the king-bolt being made to interlock with the adjacent sleeves of the head-

block and axle, and the upper perch-plate provided with pillow having recess b^6 , in which that portion of the fifth-wheel at the perch 70 rests, substantially as and for the purposes specified.

17. In a combined head-block and fifth-wheel and king-bolt, the head-block provided with sleeve A, located at rear of head-block, and 75 axle provided with king-bolt sleeve likewise located at the rear of the head-block, and perch having sleeve B, located between the sleeves A and C, and socketed into said sleeves A and C, the perch likewise having the sleeve 80 D, located below the sleeve C and socketed into the same, the said sleeves embracing the king-bolt, substantially as and for the purposes specified.

18. In a combined head-block and fifth-wheel and king-bolt, the head-block provided with sleeve A and the axle provided with sleeve C, the perch having sleeve B, located between the sleeves A and C, and also having the sleeve D, located below the sleeve C, 90 said sleeves embracing the king-bolt and the upper fifth-wheel braced to the perch, the sleeves A, B, C, and D interlocking with one another by means of ridges and recesses, 95 substantially as and for the purposes specified.

19. The combination of the axle, head-block, king-bolt sleeve located at the rear of the axle, king-bolt, perch, and fifth-wheel, the head-block being provided with sleeve A and the 100 axle with sleeve C, and perch having forwardly-extending arms b and d , respectively provided with the sleeves B and D, the sleeve B being socketed between the upper sleeve A and lower sleeve C, and the sleeve D being 105 socketed within the lower end of the sleeve C, the upper half of the fifth-wheel being rigidly united to the perch by the connecting brace or braces a^5 , the perch being provided with a pillow having a recess p^6 , supporting, 110 guiding, and securing in place the rear portion of the lower fifth-wheel, substantially as and for the purposes specified.

20. In a carriage-gear, the combination of the head-block having king-bolt sleeve A, located at the rear, and the axle having the sleeve C, located at the rear, and the double perch provided with a solid double metallic casing extending over and connecting together the two perches united thereto, the metallic casing being provided with the king-bolt sleeves B and D, the upper perch-sleeve D being directly between the sleeve A and the head-block sleeve B and the axle-sleeve C, and the lower perch-sleeve being 120 below 125 said sleeves A, B, and C, and the king-bolt passing through said sleeves A, B, C, and D, substantially as and for the purposes specified.

21. In a carriage-gear, the combination of 130 the axle and head-block, the head-block provided with king-bolt sleeve A, and the axle provided with king-bolt sleeve C, and the drop-perch provided with the brace b , the top

- of the perch being below a horizontal plane passing through the center of the space between the head-block and axle, the perch carrying king-bolt sleeves B and D, the former 5 embraced between said sleeves A and C, the king-bolt passing through these three sleeves, and also through sleeve D, located below sleeves A, B, and C, substantially as and for the purposes specified.
- 10 22. In a carriage-gear, the combination of the head-block having king-bolt sleeve A, located at the rear, and the axle having the sleeve C, located at the rear, and the double perch provided with a solid double metallic 15 casing extending over and connecting together

the two perches united thereby, and the rearwardly-extending fifth-wheel located upon the perch, the upper half of the fifth-wheel being braced thereby, substantially as and for the purposes specified. 20

23. In a vehicle-gear, the rearwardly-projecting hubs attached to the axle, perch-irons, one capped over one of the said hubs and the other socketed in the other projecting hub, substantially as and for the purposes speci- 25
